LEWIS L. CORCORAN, OF JACKSON HEIGHTS, NEW YORK, ASSIGNOR TO THE UNITED STATES GAUGE COMPANY, OF NEW YORK, N. Y., A CORPORATION OF PENNSYLVANIA

METHOD AND APPARATUS FOR AUTOMATICALLY CONTROLLING THE CHARACTER OF DISCHARGE FROM A MULTIFLUID PUMPING SYSTEM

Application filed February 7, 1930. Serial No. 426,618.

This invention relates to pumping systems of the type in which more than one distinct fluid is drawn into the system and thereafter forced into a single conduit wherfrom the commingled fluids may be discharged under pressure for exterior use. More particularly, this invention is concerned with pumping systems in which a liquid and a gas are separately drawn into the pumping apparatus and then discharged in commingled relation into a common conduit from which they may be discharged for use into the atmosphere during the pumping operation.

Still more specifically, the present invention relates to fresh water supply systems wherein pumping apparatus delivers water into a storage reservoir in which a volume of air under pressure is maintained above the liquid level for forcing water into distributing pipes when the pumping apparatus is idle. In systems of this type the pumps usually are electrically controlled by mechanism responsive to reservoir pressures, it being desirable to start the pumps only at infrequent intervals and between such intervals to utilize the reservoir air pressure for forcing the stored water through the distributing lines when the faucets are opened. These systems would operate satisfactorily but for the fact that the air is gradually absorbed and entrained in the water drawn from the reservoir until finally the reservoir becomes water-logged, with the result that the pumping apparatus is caused to start each time that a faucet is opened to withdraw water from the system. Various methods have been devised for replacing the lost air with atmospheric air, one of which consists in admitting air as well as water to the pumping apparatus which normally delivers into the reservoir, and controlling said air admission in accordance with the demands of the reservoir. The latter method and system therefor are generally satisfactory except when such a condition arises that a faucet is opened while the pumping apparatus happens to be recharging the reservoir, or the pump begins to operate while someone is drawing water through the faucet.

Should someone open a faucet when the

pump is operating, the entrained compressed air in the delivery side of the system (outside the reservoir, and particularly in the air chamber of the pump) has a tendency to expand suddenly and cause fluid to be released through the faucet with such force as to damage or knock a receptacle out of the hand of the faucet operator. Furthermore, the water continues to flow from the faucet with sufficient entrained air to cause an irregular flow with attendant gushing and splashing of water over a relatively large area surrounding the faucet. At frequent intervals the air chamber becomes filled with air and then suddenly empties itself through the open faucet.

Accordingly, it is a primary object of my invention to remedy the above mentioned defects and disadvantages.

It is an object of this invention to devise a method, and apparatus therefor, for automatically controlling the character of the fluid discharged from a multi-fluid pumping system. More specifically, it is an object of this invention to control the admission of a gas into a combined liquid and gas pumping apparatus in accordance with the position of a valve which opens or closes the discharge side of the pump to atmospheric pressure.

Another object of the invention is to provide, in a water supply system of the reservoir type in which air and water are pumped into the reservoir, means responsive to faucet manipulation to shut off the air intake when the liquid pump is running with the faucet open, and to open the air intake when the pump is running with the faucet closed. In this connection, it is a further object to convert any system already in use into one of the foregoing nature by the addition of a pressure-responsive valve in the air intake line.

It is also an object of my invention to provide a novel type of two-fluid pressure-responsive valve assembly which shall be of simple and inexpensive design and which shall embody a valve unit easily removable for replacement or repair.

Other and further objects will become apparent from a study of the following detailed

description when taken in connection with the accompanying drawings, in which:

Figure 1 shows, somewhat diagrammatically, the application of my invention to one type of water supply system known in the art.

Figure 2 discloses, in enlarged vertical section, a preferred form of pressure-responsive valve utilized in the system of Figure 1.

Referring to the drawings, in which like characters designate like parts, numeral 3 indicates the floor line upon which the system is mounted as, for example, the floor of a basement supporting the working apparatus which supplies water through distributing lines to faucets throughout the rooms of the building above. Numeral 4 designates the base of a pumping unit which comprises a flywheel 5 (driven by an electric motor, not shown) for operating a conventional liquid pump 6 having an air dome or chamber 10. The pump receives water through a supply pipe 7 and discharges it into a delivery line comprising a pair of short pipe sections 8 and 9 respectively connected through a four-way coupling 11 and in communication with a main distributing pipe 12 that is threaded into said coupling. Various branch lines one of which, 13, is shown, lead to supply valves in the nature of faucets 14. With the pump running, if a faucet is open, some of the liquid is pumped directly from pipe 8 through the pipes 12 and 13 to the faucet; but when all faucets are closed the discharge of the pump passes directly through pipes 8 and 9 to a reservoir 15 to be stored therein for subsequent use beneath a predetermined volume of compressed air. The air serves, when its pressure is high enough and the pump is not operating, to expand and force the stored water upwardly through the system for use at the faucets. Any conventional pressure-responsive controlling device (not shown) may be connected to the reservoir to start and stop the electric motor in well known manner.

A pair of conventional check valves 16 and 17 are disposed in pipe sections 8 and 9 respectively. The valve 16 closes pipe 8 when the pump is idle and opens when the pump exerts a discharge pressure above that maintained in the reservoir. Valve 17 opens line 9 when the pump is idle, and likewise maintains line 9 open when the pump is running with all faucets 14 closed, but closes the line 9 when the pump operates with faucet 14 open.

Mechanism is provided for maintaining an adequate air supply in the top of the reservoir, including an air line 18, 19 through which atmospheric air may be drawn into the snifter valve 21 on the intake side of the pump and thereafter delivered under pressure, along with the discharged water, through pipes 8 and 9 into the reservoir. A liquid-level-controlled device may be employed, of the type fully disclosed and claimed in a pending application Serial Num-

ber 316,041, filed October 30, 1928, for the purpose of regulating the admission of air from the atmosphere into line 18, 19. Briefly described, this comprises a valve 22 which is opened and closed by an arm 23 as the latter is oscillated by a float 24 when the liquid level rises and falls respectively. The element 25 is a gauge for indicating reservoir pressure.

It may happen that a faucet 14 is opened during one of the periodic intervals that the pump is operating to replenish the supply of water in the reservoir, at which time the atmospheric air valve might also be open. Under such condition, if the air pipes 18 and 19 were in direct communication with each other, the air collected in the pump chamber 10 and entrained in the distributing pipes, would suddenly tend to expand to atmospheric pressure and spurt from the faucet with great force, and would also cause a splashing and spattering of water, with periodic gushing of pent-up air, as long as the faucet remained open. To correct this defect in existing systems I have provided means for cutting off the air supply as follows:

A special valve assembly 26 (see also Figure 2) is inserted in the air line 18, 19. This assembly comprises a pair of castings 27 and 28, the upper one 27 of which is provided with an annular locating boss 29 which bears against a washer 31 and the periphery of a diaphragm 32. These parts are maintained in sealing engagement by machine screws 33. The castings are shaped to provide chambers 34 and 35 in which the diaphragm may flex in response to pressures. The upper casting is provided with a nipple 36 which may be screwed into the lower side of the four-way coupling 11, and an interior passageway 37 extends from one end of the nipple to the other whereby chamber 34 is always in communication with the interconnected ends of pipes 8, 9, and 12.

The lower casting 28 receives an elongated threaded valve housing 38 which is detachably sealed and locked in position by a soft washer 39, a hard washer 41 and a lock nut 42, and which has a nipple extension 43 to which air pipe 18 is connected by a coupling 44. A passage 45 through the valve housing 38 places pipe 18 in communication with diaphragm chamber 35. A similar passage 46 and a nipple coupling extension 47 are employed to establish communication between air pipe 19 and chamber 35. An inexpensive valve such, for example, as the conventional pneumatic tire type, is screwed into the passage 45 of the valve housing to control the communication of said passage with the other passage 46 by way of chamber 35. This conventional valve comprises the usual screw threaded seat block 48 having a conical seat 49, stem 51 having an upper actuating extension 52, guiding and reactance spider 53 and 123

valving element 54 forced by spring 55 against said seat 49 to maintain the valve closed. By pressing downwardly on stem extension 52 the valve 54 may be forced from its seat against the resistance of the spring.

Centrally of the diaphragm 32 and on the lower side thereof there is secured, by solder or the like, a disc 56 having a central integral actuating pin 57. A coil spring 58 surrounds this pin and reacts in compression against disc 56 and the upper surface of casting 28. The pin 57 is adapted, upon downward flexure of the diaphragm, to depress extension 52 and thus open the valve, but the spring 58 is strong enough to prevent this action when the pressure above the diaphragm is below a predetermined value. In some installations the inherent tendency of the flexible diaphragm to return to its flat position may be sufficient to eliminate the necessity of utilizing spring 58.

Assuming that the pump is operating and that the float controlled device has opened atmospheric valve 22, and further assuming that the faucet 14 is opened, as illustrated, the pressures in pipes 13, 12 and 8 fall immediately as a result of the opening of the faucet to atmosphere. This results in a similar decrease in pressure atop the diaphragm 32 and the spring 58 lifts the latter to permit the valve 48 to close, thereby preventing the admission of air to the snifter valve 21 of the pumps. As a result of this automatic valve operation, the pump delivers water only and a uniform and steady flow of water is obtained through the faucet. Upon closing the faucet the pump discharge pressure immediately rises, diaphragm 32 is pressed downwardly to cause pin 57 to open the air valve 48, and air is thereby again admitted to the pump to be compressed with the water and passed to the reservoir to replenish the air and water supply therein.

It should be understood that the principles of this invention are equally adapted to a number of similar uses. For example, though I have illustrated one specific type of apparatus, it is obvious that separate water and air pumps might be employed to discharge into a common conduit, the float control mechanism might be replaced by any other suitable type, and valve 48 might be mechanically or electrically controlled by movement of the faucet handles. Likewise, a similar automatic system might be employed in connection with other liquids and gases than water and air; and with carbonating apparatus to prevent, during charging of said apparatus, the escape of carbon dioxide gas from the faucets when the latter are opened at the soda fountain. As is proper and well understood, the scope of this invention is to be ascertained from a study of the following appended claims.

I claim:

1. The method of withdrawing only a liquid from the discharge side of an apparatus which normally pumps a liquid and a gas in commingled relation into a distributing system, consisting in the steps of tapping the distributing system at a point where withdrawal of the liquid is desired, and, simultaneously, automatically in response to said tapping operation, stopping the admission of gas to the pumping apparatus.

2. A pumping system comprising in combination, a pumping apparatus; a storage reservoir; means for admitting a liquid and a gas to said pumping apparatus to be placed under pressure thereby; means for delivering the compressed gas and the liquid from said pumping apparatus to said reservoir, whereby said compressed gas tends to displace said liquid from the reservoir; a distributing line connected to said delivery means so that it may receive either the pump discharge or the liquid from said reservoir, said distributing line including means for withdrawing liquid therefrom; a valve in said means for admitting gas to the pumping apparatus; and means, automatically responsive to manipulation of said withdrawing means, for opening and closing said valve.

3. In the combination set forth in claim 2, said automatically responsive means being designed to close said valve when said withdrawing means is opened during the time that the pumping apparatus is being operated, whereby no gas is ever discharged through said distributing line and its withdrawing means.

4. In the combination defined in claim 2, said automatic means comprising a pressure-responsive device in communication with said distributing line and hence responsive to pressure variations caused in the latter by opening and closing movements of said withdrawing means.

5. In a water supply system that consists in a distributing line which either may receive water from a reservoir or a mixture of air and water from a pumping apparatus; a two-fluid pressure responsive valve comprising a casing having an air passage one end of which is adapted for communication with the atmosphere and the other end of which is designed for connection to the inlet side of the pumping apparatus, an auxiliary normally open valve mounted in said casing to control said air passageway, and a pressure-responsive device designed for connection to the distributing line and adapted to close said auxiliary valve upon the reduction of the pressure in said line to a predetermined value.

6. In a water supply system, a storage reservoir; a pumping apparatus for receiving water and air and delivering them together under pressure to said reservoir whereby a

- column of water is maintained beneath a column of air in said reservoir; a water inlet line connected to the pumping apparatus; an air supply line connected between said pumping apparatus and the atmosphere, including a shut-off valve controlled by conditions within the reservoir; a water distributing line in communication with the reservoir at a point below the normal water level therein and also in communication with said pumping apparatus, whereby said line is adapted to receive water from the reservoir or to receive the fluid discharged by said pumping apparatus; means for tapping water from said distributing line; and means, automatically operable in response to manipulation of said tapping means, to stop the admission of air through said air supply line to said pumping apparatus.
- 20 7. In the combination set forth in claim 6, said pumping apparatus including a single conduit for conveying the pump discharge to said reservoir; means for coupling said distributing line to said single conduit; and a pair of check valves disposed in said single conduit, one at each side of said coupling means.
8. A pumping system comprising, in combination, a pumping apparatus; a pair of fluid conduits, one for supplying a liquid to the pumping apparatus and the other for supplying a gas thereto; a single conduit for receiving the fluids as they are discharged from said apparatus; means for withdrawing the fluids from said single conduit; and means, automatically operable in response to manipulation of said withdrawing means, to control the admission of the gas to said apparatus; said automatically operable means serving to close off said gas supply when the withdrawing means is opened, whereby only a liquid medium is discharged from said pumping apparatus when the withdrawing means is open.
- 45 In testimony whereof I affix my signature.
